(57) **CLAIM**

The ornamental design for a jewelry article, as shown and described.

DESCRIPTION

FIG. 1 is a perspective view of a jewelry article;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In FIGS. 1-7, the dash-dash broken lines shown illustrate portions of the jewelry article and the dot-dash broken lines illustrate bounds of the claim. The broken lines form no part of the claimed design.

1 Claim, 5 Drawing Sheets
